AUTOMATIC OILER, INITIAL AND DRIP

George T. Pfleger, Los Angeles, Calif., assignor to
United States Electrical Manufacturing Company, Los Angeles, Calif., a corporation of California

Application May 24, 1932, Serial No. 613,322

11 Claims. (Cl. 184—6)

My invention relates to a novel form of oiling device which finds particular utility in combination with a deep-well turbine pump.

The conventional deep-well turbine pump includes a pump unit positioned in the well and providing impellers which move the water or other well liquid upward in a discharge pipe to the surface of the ground. A line shaft extends downward through the discharge pipe and is journaled at frequent intervals throughout its length, this shaft usually being retained in a shaft-enclosing tubing. A motor is positioned at the top of the well and drives the shaft, and difficulty has sometimes been encountered in properly lubricating the line-shaft bearings. The conventional mode of effecting this lubrication is to slowly drip oil downward through the shaft-enclosing tubing, this oil dripping successively through the bearings. When the pump is not in operation, however, this drip device is usually shut off.

I have found that a continuous drip system of lubrication is not effective in properly lubricating the line-shaft bearings immediately after the pump is set into operation, and it is an object of this invention to provide an apparatus for first supplying to the uppermost line-shaft bearing a surge of oil at or near the time that the pump is set into operation, followed by a greatly restricted flow. This preliminary surge of oil quickly moves downward around the line shaft and through the bearings, thus establishing oil films in each bearing. Once these films are established a slow drip of oil to the uppermost bearing will maintain these films.

Another object of the invention is to provide an oiling device for the bearings of a deep-well turbine pump, in which oiling device a reserve supply of oil is maintained between the main reservoir and the control valve so that when this control valve is opened this reserve supply will immediately drain into the bearings.

Further objects of the invention lie in the use of such a control valve which is automatically opened when the motor or other drive means is energized.

Still further objects of the invention lie in a novel oiling system per se including a reservoir for retaining the main body of oil, and the drip device communicating therewith and discharging into a suitable storage means, the flow from the storage means being controlled by a suitable valve.

Other objects and advantages of the invention lie in the particular construction of the oiling

device to be hereinafter described including the use of a novel storage means.

Referring to the drawing,—

Fig. 1 illustrates a conventional deep-well turbine pump including the invention, this view being partially in section and partially in elevation.

Fig. 2 is an enlarged view of a portion of Fig. 1 and illustrates in detail the features of the invention.

My invention finds particular utility in combination with a deep-well turbine pump. In Fig. 1, I have illustrated one type of deep-well pump installed in a well 10 in which is placed a casing 11, the lower end of which may be perforated in the usual manner so that water or other well liquid may enter the casing. A pump unit 12 is suspended in the casing 11 on a discharge pipe 13 in the usual manner, the upper end of this pipe being supported from a pump head 14 which includes an elbow 15 for discharging the well liquid 16 pumped upward in the discharge pipe 13 by the pump unit 12. In the form shown, this pump unit is formed of a plurality of bowls 16 with a suitable strainer 17 secured at the lower end and through which the water enters the lowermost of these bowls. Each bowl includes an impeller, not shown, so that the water moves upward in succession through the impellers and through the discharge pipe 13.

These impellers are mounted on a line shaft 20 which extends upward in a shaft-enclosing tubing 21 to the surface of the ground and through the pump head 14. The shaft-enclosing tubing 21 is secured both to the pump unit 12 and to the pump head 14. In the form illustrated the upper end of this shaft-enclosing tubing is threaded into an opening 23 of the elbow 15. The line shaft 20 can be journaled at frequent intervals throughout its length, this being accomplished by sleeve bearings 25 spaced vertically above each other in the shaft-enclosing tubing 21.

One method of lubricating such bearings is to provide a drip device which slowly drips oil into the upper end of the shaft-enclosing tubing 21, as, for instance, through a pipe 26 communicating therewith. This slow drip of oil gradually moves downward through the bearings in succession. When the pump is not in operation, however, it is usually desirable to eliminate this small supply of oil, otherwise the amount of oil used would present a serious economic loss. However, eliminating this drip of oil results in a condition wherein the oil tends to drain from the shaft-enclosing tubing, thus destroying the oil films ordinarily present in the bearings 25 and separat-

- ing these bearings from the shaft. When the pump is next set into operation these bearings will be dry until oil is supplied thereto by the conventional drip device connected to the pipe 26. I have found that it requires a material length of time for a sufficient amount of oil to enter the shaft-enclosing tubing 21 to effectively lubricate the bearings 25 therein, thus resulting in undue wear on the bearings. It is my invention to supply a preliminary surge of oil to the shaft-enclosing tubing to quickly lubricate these bearings during the starting up of the pump and to thereafter supply a restricted flow of oil sufficient to maintain the oil films in the different bearings.
- These results may best be accomplished by the use of an oil-control device indicated in general by the numeral 28 which controls the flow of oil from a reservoir 29 into the pipe 26. The reservoir 29 may conveniently be positioned at the upper end of the pump head 14 and below a motor 30 drivably connected to the upper end of the line shaft 20. In this event it is usually desirable to utilize a collar 31 extending upward from a lower wall 32 of the reservoir 29, this collar extending above the normal level of oil in this reservoir, this level being indicated by the numeral 33. Oil may be supplied to the reservoir through a fitting 34, and flows therefrom through the control device 28 which will now be described.
- Referring particularly to Fig. 2, the control device 28 includes a drip device 38 which may be of conventional form. In Fig. 2, I have disclosed this device as comprising a needle valve including a pointed stem 40 which seats in a partition 41 of a valve body 42 so as to control the flow of oil through the valve body by suitably adjusting the stem 40. The oil dropping from the body 42 passes through an indicating device 45 which may include a glass window through which the drops may be seen so that the drip device 38 can be set to supply the desired amount of oil. A nipple 47 extends between an elbow 48 communicating with the indicating device 45 and a T-fitting 50, there being a stand-pipe 51 which communicates with the T-fitting and extends upward through a gland 52 into the reservoir 29 and terminates at a level above the surface 33. The gland 52 may be used to compress a packing around this stand-pipe so that no leakage takes place. A pipe 58 communicates between the T-fitting 50 and a valve means 60.
- In the form of the invention shown in Fig. 2, this valve means comprises a body 61 including intake and discharge chambers 62 and 63 separated by a partition 64, the latter chamber 63 communicating with the pipe 26. This partition includes an opening 65 which forms a valve seat for a plunger 66 which, in the preferred form of the invention, is electrically operated. In Fig. 2, I have shown a magnetic device 67 which will, when energized, lift the plunger 66, and retain this plunger in an uppermost position as long as the device is energized, thus allowing oil to move through the valve 60 and the pipe 26 to the uppermost bearing. The magnetic device 67 may, for instance, comprise a solenoid including a winding 70. This winding may be manually energized from a suitable source of current, but in the preferred form of the invention I prefer to connect this winding by conductors 71 and 72 to conductors 73 which supply current to the motor 30. A switch 74 of the usual type is used to control the energization of the motor 30 and thus also controls the energization of the winding 70. It will thus be clear that when the motor is first energized the plunger 66 will be moved upward to open the valve 60.
- The stand-pipe 51, in conjunction with the drip device 38 and their cooperating fittings, and the intake chamber 62 cooperate in defining a storage means which receives the supply of oil from the reservoir 29 in a manner to store a preliminary charge of this oil which is released as soon as the valve 60 is opened, after which the drip device 38 will throttle the flow to the bearings as determined by the setting of the needle valve included in the drip device. It should be understood, however, that I am not limited to the exact design of storage means shown, inasmuch as any storage chamber between the reservoir 29 and the valve 60 might be utilized regardless of whether a stand-pipe is used and regardless of whether the stand-pipe is open at its upper end or extends into the reservoir 29. It is usually desirable to use some sort of vertically extending chamber as a part of the storage means, but by suitably enlarging other elements cooperating in defining the storage means, it is sometimes possible to dispense with such an upward extending chamber.
- When a storage means of the type shown in Fig. 2 is utilized, it will be clear that during the time that the pump is not operating, the valve 60 will be closed and oil will drip from the reservoir 29 through the drip device 38 and will fill the elbow 48, the T-fitting 50, the nipples 47 and 58, as well as the intake chamber 62 of the valve 60. This oil will also rise in the stand-pipe 51, and if the upper end of the stand-pipe is open, as shown in Fig. 9, the oil will rise therein to a level indicated by the numeral 76 which level corresponds to the level 33 in the reservoir. Thereafter no flow will take place through the drip device 38 due to the static balance maintained by the level of oil in the stand-pipe. As soon as the motor 30 is energized, however, the plunger 66 will rise and the oil in the storage means will quickly flow through the valve 60 and to the uppermost bearing 25 whence it will drop quickly downward to properly lubricate all of the bearings in the shaft-enclosing tubing 21. Once proper films of oil are established in these bearings, it is only necessary to supply a small amount of additional oil and this is automatically taken care of in the oil-control system of the invention, for when the oil is drained from the storage means, the oil supplied to the shaft-enclosing tubing 21 will be controlled by the setting of the needle valve in the drip device 38, this needle valve thus acting as a throttle means.
- Various modifications of the invention are possible and fall within the scope of the appended claims, and it should not be understood that I am limited to the exact apparatus disclosed.
- I claim as my invention:
1. In combination with a deep-well turbine pump including a pump unit positioned in a well, a shaft, and bearings for said shaft; walls defining a reservoir containing a body of oil; a storage means adapted to receive a supply of said oil from said reservoir; throttle means through which said storage means and said reservoir are in communication; a valve means communicating with said storage means and with said throttle means for passing a surge of oil followed by a slow flow of oil, said slow flow of oil being controlled in amount by said throttle means; means communicating between said valve means and said bearings and conducting both the preliminary surge of oil and the later slow

flow of oil to said bearings when said valve means is opened.

2. In combination with a deep-well turbine pump including a pump unit positioned in a well, a shaft, and bearings for said shaft: walls defining a reservoir containing a body of oil; a storage means adapted to receive a supply of said oil from said reservoir; throttle means through which said storage means and said reservoir are in communication; a valve means communicating with said storage means and with said throttle means for passing a surge of oil followed by a slow flow of oil, said slow flow of oil being controlled in amount by said throttle means; means communicating between said valve means and said bearings and conducting both the preliminary surge of oil and the later slow flow of oil to said bearings when said valve means is opened; an electric motor driving said shaft; and an electric control means for said valve and electrically connected to said electric motor for opening said valve means when said electric motor is energized.

3. A combination as defined in claim 1 in which said storage means includes a vertically extending chamber in which said oil flowing through said throttle means rises when said valve means is closed.

4. A combination as defined in claim 1 in which said storage means includes a stand-pipe open at its upper end and extending to a point above the oil level in said reservoir whereby the oil moves through said throttle means into said stand-pipe when said valve means is closed.

5. In combination with a deep-well turbine pump including a pump unit positioned in a well, a shaft, bearings for said shaft, and a shaft-enclosing tubing retaining said bearings and surrounding said shaft; a pump head defining a reservoir at the top of said well and containing a body of oil; a drip device withdrawing oil from said reservoir at a slow rate; a storage means communicating with said drip device and into which said oil dripping through said drip device is temporarily stored; a valve means through which the oil in said storage means flows when said valve means is opened; means delivering the oil flowing through said valve means to the upper end of said shaft-enclosing tubing; and means for opening said valve means when said pump is set into operation whereby the oil in said storage means quickly flows into said shaft-enclosing tubing when said valve means is first opened to form a preliminary surge of oil, said drip device thereafter controlling the flow to said shaft-enclosing tubing through said storage means.

6. In combination with a deep-well turbine pump including a pump unit positioned in a well, a shaft, and bearings for said shaft; means at the top of said well for retaining a body of oil; supply means communicating between said oil and said bearings; a valve means in said supply means operative when opened to deliver to said bearings a surge of oil and a slow flow of oil to said bearings thereafter; a drive means for said

shaft; and means for opening said valve means when said drive means is put into operation.

7. In combination: a pump unit positioned in a well; a shaft extending upward in said well from said pump unit; bearings for said shaft and spaced vertically from each other throughout said well; walls at the top of said well defining a reservoir containing a body of oil; means delivering to the uppermost bearing a preliminary surge of said oil; and means for subsequently delivering a slow drip of oil to said bearings.

8. A lubricating device for lubricating bearings vertically spaced from each other whereby lubricant delivered to the uppermost bearing drops successively through said bearings, including in combination: pipe means communicating with the uppermost of said bearings; a storage means containing a quantity of lubricant; a valve means in said pipe means and including a relatively large flow passage for quickly conducting said quantity of lubricant to said uppermost bearing; and means communicating with both said pipe means and said storage means for delivering a small quantity of lubricant to said pipe means after said quantity of lubricant has been discharged therefrom.

9. A lubricating device for lubricating bearings vertically spaced from each other whereby lubricant delivered to the uppermost bearing drops successively through said bearings, including in combination: pipe means communicating with the uppermost of said bearings; a storage means containing a quantity of lubricant; a valve means in said pipe means and including a relatively large flow passage for quickly conducting said quantity of lubricant to said uppermost bearing; and means automatically renewing said quantity of lubricant in said storage means when said valve means is closed, said means communicating with said pipe means.

10. A lubricating device for lubricating the vertically spaced bearings of a deep-well turbine pump, including: walls defining a reservoir containing a lubricant; walls forming a storage means; means for delivering lubricant from said reservoir to said storage means until a static pressure balance exists in said reservoir and said storage means; and means for quickly draining said lubricant from said storage means and delivering this lubricant to the uppermost bearings.

11. In combination with a deep-well turbine pump including a pump unit positioned in a well, a shaft, and bearings for said shaft: a pump head defining a reservoir containing a body of oil; a storage means including a stand-pipe extending into said reservoir and terminating at a point above the level of said body of oil; throttle means communicating between said reservoir and said stand-pipe; pipe means communicating between said stand-pipe and the uppermost bearing; a valve in said pipe means; and means for opening said valve when said pump unit is set into operation.

GEORGE T. PFLEGER.
